CLAIM

The ornamental design of a front-mount mower, as shown and described.

DESCRIPTION

FIG. 1 is a top plan view of our front-mount mower;

FIG. 2 is a front view thereof;

FIG. 3 is a rear view thereof;

FIG. 4 is a right side view thereof;

FIG. 5 is a left side view thereof;

FIG. 6 is a perspective view thereof;

FIG. 7 is a perspective view thereof;

FIG. 8 is a perspective view thereof; and,

FIG. 9 is a perspective view thereof.

The claim is directed to that which is shown. The bottom view is not part of the invention.
